SAFETY TUBES OR THE LIKE

Frederick A. Krusemark, Chicago, Ill.

Application November 22, 1939, Serial No. 305,608

11 Claims. (Cl. 152—342)

This invention has to do with safety tubes or the like for use in automobiles and other vehicles using air-inflated tires and tubes. It is a continuation in part of the subject matter contained in my patent application, Serial No. 247,334, filed December 23, 1938, on Safety tubes, which matured into Patent 2,264,164 November 25, 1941.

It is a purpose to provide a safety tube of the generally described multiple chamber type, in which one of the chambers fits over the other chamber, in a manner generally crescent-shaped in cross-section, as set out and described in my previous application, but in which in this application the base portions of the outer chamber are fastened together across the base of the inner air chamber.

It is a further object to provide a fastening means which is substantially continuous in longitudinal area of the safety tube, but which itself usually contains no air or inflating fluid, merely serving the purpose of tying the base portions of one air chamber unit of the safety tube together generally across the base of the other air chamber unit of the safety tube, and the other purposes described below. It is another purpose and object of the invention to provide a substantially continuous lengthwise strip of material which fastens the base portions of one air chamber unit of the safety tube together, and which acts at the same time as a protecting flap or shield for the base portion of a second air chamber unit of the safety tube.

It is a further object of the invention to provide a device as described above, which is preferably of yieldable flexible material designed to expand to allow the base of the air chamber unit it protects to move down into the well of the rim upon inflation, but which preferably will not ordinarily cause the outer air chamber unit, the bases of which are tied together by said strip of material to follow more than a limited amount. In other words the strip of material preferably is yieldable enough to permit the base of the inner air chamber unit to enter the well of the rim, and is still strong enough to hold the base portions of the outer air chamber unit in relative position, thus generally eliminating the necessity of a bead, but still permitting the bases of the outer air chamber unit to remain substantially adjacent the bead of the tire.

It is a further object to provide a structure in which the bases of the outer air chamber unit are in nowise connected directly to the base of the inner air chamber unit, but are connected

to each other across the base of the inner air chamber unit in such a way that they operate substantially independently from the operation of the base of the inner air chamber unit, and the base portions of the outer air chamber unit and flap across the base portion of the inner air chamber unit form additional protection against injury to the base of the inner air chamber unit.

It is a further object of the invention to provide a flap which is preferably in effect a continuation of the material and construction of the outer wall portion of the outer air chamber unit but which flap in itself does not enclose any air chamber; that is, a flap designed to eliminate practically all air between it and the base of the inner air chamber unit, thus allowing the base of the inner air chamber unit a freedom of movement for assuming its proper position when inflated and at the same time fully protecting the base of the inner air chamber unit and assisting in retaining the bases of the outer air chamber unit in proper position.

It is a further object to provide a construction which is substantially continuous in outer appearance, giving the impression of a single inner tube such as is on the market today; and with objectionable features causing the tube failure eliminated.

It is an object to provide a construction in which the base of the inner air chamber or tube is not unduly thick, for the reason that the base is protected by an integral flap joining the base portions of the outer air chamber unit so that a thin readily stretchable base of the inner air chamber unit is not objectionable.

It is a further object to provide a construction which may be manufactured by either a single or double cure, as desired, which is relatively inexpensive, and which may be made on machinery available and in use today.

Other objects and advantages of the invention will appear as the nature of the improvements is better understood, the invention consisting substantially in the novel construction, combination and arrangement of parts herein-after fully described, illustrated in the accompanying drawing, and finally pointed out in the appended claims.

In the drawing the figure is a fragmentary cross-sectional view of a safety tube illustrated from a perspective viewpoint, showing the features of my present invention.

Referring more in detail to the figure, number 10 is an ordinary valve stem, such as is common on the market and in use today. This valve

stem is inserted in and fastened to the inner air chamber unit or tube 11, preferably in the same manner that valve stems are inserted in ordinary inner tubes on the market. It is retained in place by vulcanizing or otherwise fastening the flared base portion 12, so that the inner air chamber is inflated through said valve stem. 5

The inner air chamber unit 11 comprises a crown portion 13, side walls 14 and 15, and a base portion 16, the parts forming an inner air containing chamber. 10

At least a part of the base portion is preferably formed of resilient material such as rubber strip 17. 15

As generally constructed, the side walls and crown portions of the inner air chamber unit are preferably of rubberized fabric or the like. 20

It is to be understood however that practically all materials used in construction of tubes are feasible for use in this structure, and it is not intended to limit the scope of this application by merely describing one material for each portion of the safety tube. 25

Preferably joined to the outside of the inner air chamber unit 11, along the side wall portions 14 and 15, is the inner side wall 18 of the outer air chamber. This inner side wall 18 is preferably constructed of rubber compound such as is in use on the ordinary inner tube construction today. Obviously other materials may be substituted, but rubber seems to be most desirable. 30

The inner side walls 18, at their other edge portions, join with the outer walls 19 to form bases 20, being fastened thereto by vulcanizing, cementing or otherwise in any well-known manner. This completes the outer air chamber unit 21 which has the outer side walls 22, the crown portion 23, and completes two effective air chambers. The inner air chamber unit is sometimes called the inner tube, and has one or more passages 24 comprising grommets or the like by which air may pass at restricted speeds from the inner air chamber to the outer air chamber. It is thus clear that the outer air chamber unit has a portion of its inner wall composed of crown portion 13 of the inner air chamber unit, and the remainder of its inner wall comprising the inner side walls 18. This is not absolutely necessary, but seems to be a preferred form. 35

The bases 20 of the outer air chamber unit 21 are joined by a flap portion 25, which preferably is a continuation of the material forming the outer walls 19 of the outer air chamber unit. The space 26 between the flap portion and the base 16 of the inner air chamber unit 11 preferably has one or more air ports 27, which serve to let the air flow out freely from the space 26. 40

As shown in the figure, these air ports may comprise holes or space left around the valve stem 10, although there may be other ports at various positions if desired. 45

Although the material forming the flap 25 is preferably a continuation of and similar to the outer walls 19 of the outer tube, it is understood that the flap may be constructed of webbing of various kinds or with large ports 27 therein. In operation, the entire assembly is mounted with an automobile tire, not shown, on a rim, not shown, and air is forced into the valve stem 10. Rapidly filling the inner air chamber with air causes the inner air chamber unit 11 to set into the well of the rim on which the tire and tube are mounted. For this purpose the rubber strip 17 has a peculiar action in seating in the well 50

of the rim. It is believed to stretch sideways in cross-section, and to compress circumferentially because the inner diameter is decreased when it goes into the well of the rim. The rapid inflation of the inner chamber is not transmitted to the outer chamber, which fills up more slowly. As the air seeps through the passage 24, the crown portion 13 of the inner air chamber unit reaches a state of balance with respect to the air on both sides thereof, and the base 16 will have become firmly seated in the well of the rim. In case of abrupt seating of the base 16, or movement which tends to pull the inner wall of the outer air chamber unit out of normal operating position, causing a fold or bend which is common in some constructions of safety tubes on the market today, the flap 25 will resist the pull of any folding movement which would tend to cause the bases 20 to move outwardly, thus keeping the inner wall of the outer air chamber unit properly aligned. Since the inner wall of the outer air chamber unit preferably is constructed to expand if necessary, the pull at the bases 20 by the flap 25, in event of excessive movement outwardly of the inner air chamber unit will hold the bases 20 in proper position. At all times, even in failure of the outer air chamber unit 21, the base 16 of the inner air chamber unit and particularly the rubber strip 17 is properly protected against rim friction and injury by the flap 25. 55

"Air chamber" is generally intended herein to designate the space containing air for inflation, and "air chamber unit" is generally intended to designate the structure forming the air chamber. This is true unless the meaning is obviously otherwise. 60

The form of the invention herein shown and described presents a preferred embodiment thereof, and delineates its adaption to practical use, but it is to be understood that the present disclosure is to be considered from the illustrative standpoint and not as imposing restriction or limitation on the invention. 65

While I have herein shown and described certain features of my invention, still I do not wish to limit myself thereto, except as I may do so in the claims. 70

I claim:

1. An inner air chamber unit with a base, side walls, and a crown portion, and an outer air chamber unit with a plurality of bases, side walls and a crown portion, said outer air chamber unit surrounding the crown portion and at least part of the side walls of the inner air chamber unit, and having its base portions fastened together by a flap across the base of the inner air chamber unit and separate and distinct therefrom, valve means passing through the flap and attached directly to the inner air chamber whereby the inner air chamber is inflated without inflating between the flap and the base of the inner air chamber, and means, in the flap, releasing at all times any entrapped air from between the flap and the base of the inner air chamber, whereby substantial air pressure above atmospheric is eliminated from between said flap and the base of the inner air chamber. 75

2. An inner tube having an inner air chamber unit with base, side walls and crown portions and an outer air chamber unit with base portions, inner walls and crown, said outer air chamber unit surrounding the crown portion and at least part of the side wall portions of the inner air chamber unit, and the base portions of said

outer air chamber being connected by a flap across the base portion of said inner air chamber, and release means in the flap, comprising air ports, whereby substantially all entrapped air is removed from between the flaps and the base of the inner air chamber during normal operations when the air chambers are inflated.

3. An inner tube comprising in combination an outer air chamber unit having outer walls, inner walls, crown and a plurality of base portions, and an inner air chamber unit having crown, side walls and base, with the crown and at least a portion of the side walls comprised of and identical with at least a portion of the inner walls of the outer air chamber unit, said inner air chamber unit base portion being separate with respect to the base portions of the outer air chamber unit, the base portions of the outer air chamber unit being connected by a flap, said flap in normal operations resting against the base of the inner air chamber throughout substantially the area of the flap, but being distinct from said base of said inner air chamber.

4. An inner tube comprising in combination an outer air chamber unit with inner walls and outer walls, crown and a plurality of base portions, and an inner air chamber unit with crown, side walls and base, with the crown and at least a portion of the side walls comprised of and identical with the inner walls of the outer air chamber unit, said inner air chamber unit base portion being separate from the base portions of the outer air chamber, the base portions of the outer air chamber being connected by flap means separate and distinct from the base of the inner air chamber unit, said flap having means comprising at least one port, eliminating substantially all air from between the flap and inner air chamber when the air chambers are inflated, and valve means for inflating the air chambers.

5. An inner tube comprising a plurality of air chambers formed of inner and outer air chamber units, the inner air chamber unit having a base, side wall and crown portions, and the outer air chamber unit having a plurality of bases, an outer wall, an inner wall, and a crown portion, the bases of the outer air chamber unit being connected by flap means, across the base of the inner air chamber unit, and means venting the space between the flap means and the base portion of the inner air chamber unit at all times whereby no substantial pressure above atmospheric exists between the flap means and the base portion of the inner air chamber unit.

6. An inner tube comprising a plurality of air chambers formed of inner and outer air chamber units, the inner air chamber unit having a base, side wall and crown portions, and the outer air chamber unit having a plurality of bases, an outer wall, an inner wall, and a crown portion, the bases of the outer air chamber unit being connected by flap means of yieldable flexible material, across the base of the inner air chamber unit, and separate therefrom, and means, in the flap, releasing air from between the flap means and the inner air chamber unit whereby atmospheric pressure is maintained at all times for any air between the flap means and the base portion of the inner air chamber unit.

7. An inner tube comprising in combination an outer air chamber unit, with inner walls and outer walls, crown and a plurality of base portions, and an inner air chamber unit having a crown, side walls and a base, with the crown and

5 at least a portion of the side walls of the inner air chamber unit comprised of and identical with the inner walls of the outer air chamber unit, said inner air chamber unit having a base portion separate with respect to the base portions of the outer air chamber unit, all of the base portions of the outer air chamber unit being connected by a flap means separate and distinct from the base of the inner air chamber unit and across the base of the inner air chamber unit, said flap forming an air retaining portion of neither air chamber unit and having means comprising an outlet port, whereby substantially all air is prevented from becoming entrapped between said flap and said air chambers, and said air chambers having valve means whereby they are inflated.

8. An inner tube of the class described having in combination an inner air chamber unit with side wall, crown and base portions, an outer air chamber unit of generally crescent shape, said outer air chamber unit having a plurality of base portions and having an inner wall joining the outer air chamber unit to the inner air chamber unit at a position above the base portion of the inner air chamber unit, and a flap connecting the base portions of the outer air chamber unit across the base of the inner air chamber unit, at least one passage for air between the inner 20 and outer air chambers, and a valve stem from the inner air chamber through the flap, by which air is conducted from a source of air such as a tire pump to the inner air chamber, and port means whereby entrapped air is removed from the space between the flap and the base of the inner air chamber, and said flap forms a protective portion over the base of the inner air chamber.

9. A safety tube for automobiles and the like 40 comprising an inner air chamber unit, having side wall, base and crown portions, forming an inner air chamber, an outer air chamber unit, with base, inner walls, and crown portions forming an outer air chamber, and at least partially surrounding said inner air chamber, and having a portion of its inner walls composed of the outer portion of at least a portion of the inner air chamber unit, the outer air chamber unit having strips of material comprising at least a portion 45 of its inner walls joining the outer air chamber to the tube comprising the inner air chamber unit at a position above the base of the latter, the outer air chamber unit having its base portions connected across the base of the inner air chamber unit by means of a flap, said flap being separated from the base of the inner air chamber unit, and having port means, eliminating substantially all air from the space between the flap and the inner air chamber during normal operation—especially when the air chambers are inflated.

10. An inner tube comprising a plurality of air chambers formed of inner and outer air chamber units having respective base portions, 55 the outer air chamber unit having two base portions extending below at least the upper part of the base portion of the inner air chamber unit, intercommunicating means for the passage of air between the air chambers, means comprising a flap connecting the base portions of the outer air chamber together across the base of the inner air chamber, the connecting means being separated from the base of the inner air chamber, valve means comprising a valve stem, passing 60 through said connecting means and discharging

directly into one of said air chambers, said structure being characterized by an absence of substantial inflation between said connecting means and said inner air chamber.

11. An inner tube comprising an inner and an outer air chamber unit, the inner air chamber unit having a base, side wall and crown portion, and the outer air chamber unit having a plurality of bases, an outer wall, an inner wall and a crown portion, the bases of the outer air chamber unit

and the base of the inner air chamber unit being separated and spaced apart, and the bases of the outer air chamber unit being connected by a flap means across the base of the inner air chamber unit, and means eliminating substantially all air pressure above atmospheric from the space between the outer air chamber unit base means and the flap, and the base of the inner air chamber unit, at all times.

FREDERICK A. KRUSEMARK.
